C. N. JOHNSON

GLASS CASKET

Filed April 29, 1924

UNITED STATES PATENT OFFICE.

CHARLES NEWTON JOHNSON, OF VINCENNES, INDIANA.

GLASS CASKET.

Application filed April 29, 1924. Serial No. 709,831.

To all whom it may concern:
 Be it known that I, CHARLES N. JOHNSON, a citizen of the United States, residing at Vincennes, in the county of Knox and State of Indiana, have invented certain new and useful Improvements in Glass Caskets; and I do hereby declare the following to be a full, clear, and exact description of the invention, such as will enable others skilled in the art to which it appertains to make and use the same.

The present invention relates to a receptacle for interment of the dead and provides a casket which is practically indestructible, odor and germ proof and which is of such formation as to be shipped in knock-down form so as to minimize transportation and storage, and which may be readily set up when required, the casket when sealed admitting of observation of the remains, thereby obviating the necessity for opening of the receptacle when it is required to obtain a view of the remains.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a top plan view of a casket embodying the invention.

Figure 2 is a vertical longitudinal sectional view thereof on the line 2-2 of Figure 1, and

Figure 3 is a detail sectional view on the line 3-3 of Figure 1.

Corresponding and like parts are referred to in the following description and designated in the several views of the drawings by like reference characters.

The casket embodies a metal frame and glass panels, the joints being such as to prevent the escape of any odor from the inside or air and moisture penetrating from the outside. The bottom, top and enclosing sides of the casket comprise glass panels which

are set into a metal frame, the construction being such as to admit of the replacement of any panel should the same become broken. 55 Angle strips 1 are provided at the top, bottom and corners and may be connected in any preferred way. Other angle strips 2 are provided at the bottom and the glass panels are confined between the inner angle strips 2 and the outer angle strips 1. The inner and the outer angle strips are adapted to be connected by bolts 3 or like fastening means. Wooden strips 4 are provided and enable the drapery and like furnishing to be 65 attached to the casket. Outer metal strips 5 and inner metal strips 6 are located opposite the joints formed between the several panels 7 and these metal strips may be bolted or otherwise fastened, as indicated at 3. The 70 usual handle bars 8 are located at opposite sides of the casket and are fastened thereto by fittings 9 which may be secured to the intermediate strips in any preferred way. A channel strip 10 is located at the top of 75 the body of the casket, the channel facing upwardly so as to receive a cementing material whereby a tight joint is obtained between the cover and the body. The cover comprises a metal frame and glass panels 80 and may include hinged sections, whereby a portion of the cover may be opened as occasion may require. It is to be understood that in assembling the parts, a cementing material is interposed between the marginal 85 portions of the panels and the metal frame and between the metal frames of the several parts so as to insure a tight joint so as to render the casket germ and odor proof as well as exclude air and moisture. 90

What is claimed is:

1. A burial receptacle comprising a bottom and enclosing walls including glass panels, an enclosing frame for said panels, said frames at the corners of the receptacle made 95 up of inner and outer angle pieces, inner and outer strips covering the joints between said panels intermediate of said corners, and means to secure the parts together.

2. A burial receptacle comprising a bottom, a top and enclosing walls including glass panels, inner and outer angle strips being provided at the bottom and corners, and inner and outer metal strips being

provided opposite the joints formed between the glass panels, a channel strip at the top of the body, and wooden strips providing means for attaching of the drapery, the 5 several joints being sealed by a cementing material to render the article odor and germ proof and to exclude air and moisture.

In testimony whereof I affix my signature in presence of two witnesses.

CHARLES NEWTON JOHNSON.
